UNITED STATES PATENT OFFICE.

ALFRED T. VOELKER, OF GLASSBORO, NEW JERSEY.

TORPEDO.

Application filed July 15, 1921. Serial No. 484,908.

To all whom it may concern:

Be it known that I, ALFRED T. VOELKER, a citizen of the United States, residing at Glassboro, in the county of Gloucester and 5 State of New Jersey, have invented certain new and useful Improvements in Torpedoes, of which the following is a specification.

One object of my invention is to make a toy torpedo of a novel construction which 10 can be easily and cheaply manufactured and at the same time can be easily handled and packed without breaking.

Another object is to so produce my improved torpedo that while it can be cheaply 15 and easily manufactured, the parts will hold together until it is fired by throwing the same.

These objects, and other advantageous ends which will be described hereinafter, I 20 attain in the following manner, reference being had to the accompanying drawings in which—

Figure 1 is a perspective view of a torpedo made in accordance with my invention,

25 Figure 2 is a perspective view showing a sheet of material, such as paper, which is rolled and illustrating one step in the formation of one of the sections of the shell of my improved torpedo,

30 Figure 3 is a perspective view showing the rolled sheet having been partially folded over one end of the rolled structure and illustrating another step in the production of my improved torpedo,

35 Figure 4 shows said section completed,

Figure 5 is a detached perspective view of the sections of the shell in a position illustrating that one of the sections can be telescopically slid in the other section with the 40 closed ends opposed to each other and including therebetween a filling of explosive material,

Figures 6 and 7 represent enlarged sectional views of the shell sections detached, 45 and

Figure 8 is a sectional view of the completed torpedo.

Referring to the drawing, my improved torpedo includes a shell 9 made up of two 50 cup-shape sections 10 and 11. These cup-shape sections 10 and 11 are similarly constructed with the exception that the section 10 is of slightly smaller external diameter than the section 11 so that the sections, 55 which are preferably of cylindrical form,

can be slid one into the other by exerting a slight pressure; the friction between the sections being sufficient to hold them in their telescoped position as shown in Figure 8, and to include therebetween a filling 12 of 60 explosive material. Preferably a coating of adhesive material is placed on either or both of the sections so that when they are forced together they will be secured one to the other. If desired the external diameter 65 of the section 10 can be made slightly greater than the internal diameter of the section 11 so that it will be necessary during the telescoping movement of the sections to slightly expand the diameter of the 70 section 11. This latter also tends to securely hold the sections together.

I make the sections 10 and 11 in a novel manner hereinafter described and since both of the sections are similar with the 75 exception of their diameters I will describe the manner of producing one of the sections and it will be understood that the other section is similarly made.

Referring first to Figure 2, I use a sheet 80 13 of non-metallic fibrous material such as paper; said sheet being made in strip form and this sheet is first rolled as shown at 14. This rolling, if desired, may be done upon a mandrel (not illustrated). I then fold 85 the end portion 15 of the rolled sheet by first pressing said portion 15 as shown in Figure 3; the initial folding preferably taking place at the portion which includes the outer edge 16 of the sheet. A series of 90

these folds are made as shown at 17 in Figure 4 so as to provide a closed end 18. The portion of the sheet which is to be folded is preferably coated with adhesive material so that when folded the flaps of 95

the folds will remain in their folded positions. Also by using a thin flexible tough paper the fold when thus made will retain its position; the intersection of the flaps with the cylindrical surface 19 preferably 100 being made sharp or abrupt. This completes the making of the cup section and by telescoping two of these sections together with their closed ends 18 opposed to each other, as shown in Figure 8, and having the

filling of explosive material therebetween, the torpedo will be completed. I preferably 105 make the sections 10 and 11 of such length that when they are put together the closed end of the section 10 will be flush 110

with the edge of the open end of the section 11.

It will be noted that by thus making the cup sections that each section will have an integral closed end or in other words an end which is formed of the same material out of which the sides of the section are produced.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claim.

Having thus described my invention, what

I claim as new and desire to secure by Letters Patent is:—

A torpedo consisting of two telescoping cup sections of different diameter each made of fibrous material and having one end closed, the cups being adapted to telescope throughout their length and the smaller of the cups containing a charge of explosive material.

In testimony whereof I have signed my name to this specification in the presence of two subscribing witnesses.

ALFRED T. VOELKER.
